UNITED STATES PATENT OFFICE

CLARENCE B. HARBISON, OF LIMA, OHIO, ASSIGNOR TO THE OHIO STEEL FOUNDRY COMPANY, OF LIMA, OHIO, A CORPORATION OF OHIO

SIDE FRAME SECTION

Application filed April 7, 1930. Serial No. 442,052.

This invention relates to improvements in side frames of railway trucks and has for its principal object to provide an improved form of transverse section for the tension and compression beam members of the side frame whereby the frame may be cast with greater strength, but with less danger of cracking than with present standard constructions.

One of the most widely used beam sections now employed in cast side frames is known as the U-section in which the corners formed by the two upright and cross webs of the section usually require the addition of transverse fins or webs, generally termed "cracking brackets", disposed at intervals of a few inches along the inner angles of said corners, so as to prevent the member from cracking during cooling. I find, however, that by modifying the shape of the beam section so that the transverse web meets with the upright webs at a wider curve describing an arc of substantially more than 90°, the moment of inertia of the beam is greatly increased, and furthermore the use of cracking brackets may be entirely dispensed with.

The invention may best be understood by reference to the accompanying drawings, in which

Figure 1 is a side view of a side frame constructed in accordance with my invention.

Figure 2 is an enlarged fragmentary beam section taken on line 2-2 of Fig. 1.

Figure 3 is a modified form of beam section constructed in accordance with my invention.

Referring to details of the embodiment of my invention illustrated in the drawings, a side frame, indicated generally at 10, comprises an upper or compression beam 11, and a lower or tension beam 12 meeting at their opposite ends at journal boxes 13, 13 and separated near their center portions by upright columns 14, 14. The parts above described are arranged in their usual manner, so need not be described in greater detail.

Referring more particularly to the features of the present invention, it will be observed that the main portions of both the tension and compression beams are formed with their transverse sections comprising a

modified U-shape, as shown in Figure 2, in which the upright webs 15, 15 diverge generally toward arched corner portions 16, 16 which in turn merge into the horizontal web 17, and the corner portions 16 are curved through an arc substantially greater than 90°, as is best indicated by their center line at A-A in Figure 2. The beam is thus substantially wider near the horizontal web 17 than between the upright side webs 15, 15. The upright webs 15, 15, cross web 17, and arched portions 16, 16 are all preferably of substantially the same thickness.

The webs 15, 15 may also be provided with outwardly extending beads or flanges 15a, 15a at their free ends, in the form shown the sides of the beads being substantially flush with the widest part of the adjacent arched corner 16.

With this construction, I find that the use of cracking brackets is not necessary, as the formation of a uniformly thick walled U-section having a relatively wide base and with the side walls tending to converge inwardly from the base rather than being substantially at right angles thereto, as in ordinary U-shaped sections, practically eliminates the danger of cracking, and at the same time greatly increases the moment of inertia of the beam, particularly against lateral and torsional stresses.

In the modified form of section shown in Figure 3, the side walls merge more directly into the arched corners 16, 16 so that their center lines, indicated at B-B, are inclined toward each other throughout their length, instead of meeting their adjacent arched corners in a reverse curve, as in the form shown in Figure 2. The result in increased moment of inertia and elimination of cracking is substantially the same in both forms.

I claim:

1. In a side frame, a longitudinal beam having a generally U-shaped cross section with its two upright webs joining the transverse web in a wide curve extending through an arc substantially more than 90°.

2. In a side frame, a longitudinal beam having a generally U-shaped cross section, with its two upright webs inclined outward-

ly and joining the transverse web in a wide curve of substantially uniform thickness extending through an arc substantially more than 90°.

5 3. In a railway truck side frame, a longitudinal beam having an approximately U-shaped cross section of substantially uniform thickness, and having the sectional center lines of the two upright webs spaced apart 10 substantially more adjacent the transverse web than adjacent the free ends of said upright webs.

Signed at Lima, Ohio, this third day of April, 1930.

15 CLARENCE B. HARBISON.
